UNITED STATES PATENT OFFICE

HAROLD W. SHONNARD, OF MONTCLAIR, NEW JERSEY, ASSIGNOR TO ELEVATOR SUPPLIES COMPANY, A CORPORATION OF NEW JERSEY

LOCKING MEANS FOR SLIDING DOORS

Application filed September 20, 1926. Serial No. 136,454.

It is common practice, in connection with the operation of elevators in hotels, offices and other public buildings, to provide power operated means for opening and closing the doors at the various floors on each elevator shaft.

It is important from the point of view of public safety that each door on every elevator shaft should be securely locked, save when the elevator cage is opposite such door. The present invention relates to an improved means whereby each door may be kept locked, while at the same time permitting it to be automatically or manually unlocked when the elevator cage is in a safe position opposite the door opening.

The invention is shown in a preferred form in the accompanying drawings, wherein Figure 1 is a view of the sliding doors in elevation, provided with my present improvement, Figure 2 is a top plan view of the power operated movable locking stop, and Figure 3 is a side view of the same, partly in vertical section.

In Figure 1, the two parallel sliding floor doors, commonly used in the elevator practice are shown respectively at 10 and 11. The parallel dotted lines 12 represent the limits of a portion cut out of the door 11, and its operating toggle bar, to permit its inclusion within the sheet of drawing.

The doors 10 and 11 are operated, either through power mechanism or manually, in a well known manner, by the system of toggle arms shown. The arm 13 is mounted to turn upon the fixed pivot 14 at one extremity of the arm, while the other extremity of 13 is pivotally attached at 15 to one end of the arm 16.

The arm 16 is revolvably mounted between its ends on the door 10 on the pivot 17. The toggle arm 18 is pivotally connected with the arm 16 at 19, and its opposite extremity is pivotally connected with the sliding door 11 at 20.

At 21 is shown a handle attached to the arm 16. By drawing down on this handle, the toggle arms 13, 16 and 18 are so moved as to cause the two doors 10 and 11 to slide to the left in Figure 1, to open the door on a

given floor in a well known manner. Manual operation of the doors in this manner will usually be unnecessary, as normal opening and closing of the doors is accomplished through the power operated mechanism.

For this purpose, I have shown a well known type of pneumatic engine, comprising a cylinder 22, within which operates a piston attached pivotally to one of the toggle arms, 13, by the connecting rod 23. The compressed air, or equivalent pressure producer, is introduced through the inlet pipe 42 as is well known in this art.

In order to lock the doors, preventing unauthorized opening of the same I provide two abutments or stops, one carried by one of the doors, preferably the door 10, and the other supported by a fixture on the floor itself. These are so placed as to come into contact when an attempt is made to open the locked door, but are so constructed as to permit unlocking of the door in either of two ways, viz—either through power operated mechanism when normal power operation of the door takes place, or manually when, for any reason it becomes necessary to open the doors by hand.

In the drawings the two co-operating abutments or stops are shown respectively at 24 and 25. The abutment 24 is a lever pivoted to the door 10 at 26 and normally resting against a pin 27 on said door.

Where unlocking through the power mechanism is desired, as in the form shown, the stop or abutment 25 takes the form of a lever pivoted to a fixed support at 28, and normally resisting the pressure of the abutment or lever 24 when it is attempted to open the doors.

In order to permit manual unlocking, so that the doors may be opened by hand, the pivoted lever 24 is pivotally connected with an operating rod 29, the other end of which is pivotally connected with a bell crank 30, preferably mounted on the pivot 17 which supports the toggle arm 16.

A thumb lever 31 is pivotally supported on the arm 16 close to the handle 21, and is connected with the opposite end of the bell crank 30 by the rod 32, whose opposite extremities are pivotally connected with the

thumb piece 31 and the bell crank 30, respectively.

It will thus be seen that, if it be desired to open the doors by hand, without moving the abutment 25, the operator, as he grasps the handle 21, presses with his thumb on the lever 31, causing the bell crank 30 to tilt clockwise and lifting the end of the lever abutment 25 so that its path of movement is above and out of contact with the abutment 25.

The preferred construction whereby automatic unlocking of the doors through the power mechanism is accomplished when they are normally opened by the engine 22 is shown in Figures 2 and 3. In Figure 3, this is shown in the unlocked position.

The lever 25, pivotally supported on the shaft or pivot 28, is normally tilted upward into the locking position shown in Figure 1 by the spring 33, mounted upon the casting 34. The stop 35 prevents the lever 25 from tilting anti-clockwise beyond the locking position.

The upper portion of the casting 34 is hollowed out to form a chamber 36, normally closed by a screw cap 37, and opening on the side opposite said cap in a valve seat closable by means of a ball 38.

The chamber 36 communicates by the vertical boring 39 and the horizontal boring 40 with a branch pipe 41, leading from the main supply pipe 42 which conveys compressed air or its equivalent to the door operating engine 22. The abutment lever 25 has a tail-piece 43 which abuts against the ball 38 (See Fig. 3).

When air or other fluid pressure is admitted to the door-opening engine 22 in any well known manner through the pipe 42, this pressure is communicated through the branch pipe 41 to the interior of the casting 34, where it causes the ball 38 to assume the position shown in Figure 3, pressing the tail-piece 43 to the left and causing the right hand extremity of the pivoted abutment 25 to be depressed. This removes this abutment from the path of movement of the abutment 24, and permits the sliding doors to move toward the left in Figure 1 to open the door.

While I have described my invention herein as applied to elevator doors, it is to be understood that my invention applies to the operation of doors whether used in connection with elevators or otherwise.

Various changes may be made in my improvement without departing from the scope of my invention, which is not limited to the details herein shown and described.

What I claim is:

1. In combination with a door, a power operated abutment, a movable abutment normally held stationary, one of which is on a fixed support and the other upon the door,

said abutments preventing opening movement of the door, mechanism for moving the door, controlled power means acting to move the power operated abutment out of line with the other abutment, and power means to operate the door mechanism. 70

2. In combination with a door, toggle mechanism for moving said door, an operating handle on one of the arms of the toggle, a movable abutment on the door, a power controlled abutment upon a fixed support, said abutments being in line, a lever on the arm near the handle, and means controlled by said lever for moving the door abutment out of line with the power abutment when the power mechanism fails. 75 80

3. The combination according to claim 1, wherein means are included for normally retaining the power abutment in line with the door abutment. 85

4. The combination according to claim 1, wherein said power operated abutment comprises a spring-pressed lever and a piston for moving said lever. 90

5. The combination according to claim 1, further including a toggle mechanism for moving the door, an operating handle on one of the arms of the toggle, and means adjacent said handle for moving said movable abutment which is normally held stationary, 95 out of line with the power abutment when the power mechanism fails. 100

In testimony whereof I hereto affixed my signature on this 18th day of September, 1926.

H. W. SHONNARD.
